UNITED STATES PATENT OFFICE.

CHARLES TORREGROSSA, OF NEW ORLEANS, LOUISIANA.

DESIGN FOR A SIGNBOARD.

Application filed July 8, 1926. Serial No. 18,276. Term of patent 3½ years.

To all whom it may concern:

Be it known that I, CHARLES TORREGROSSA, a citizen of the United States, residing at New Orleans, in the parish of Orleans and State of Louisiana, have invented a new, original, and ornamental Design for a Signboard, of which the following is a specification, reference being had to the accompanying drawing, forming part thereof.

The figure is a front view in elevation of the signboard, showing my new design.

I claim:

The ornamental design for a signboard as shown.

CHARLES TORREGROSSA.
